UNITED STATES PATENT OFFICE.

OSWOLD HARRY SNAZELLE, JOHN HETHERINGTON, AND LOUIS MANTELL MCILDOWIE,
OF LONDON, ENGLAND.

APPARATUS FOR CLEANING WINDOWS AND SIMILAR PURPOSES.

Application filed March 8, 1922. Serial No. 542,104.

To all whom it may concern:

Be it known that we, OSWOLD HARRY SNAZELLE, JOHN HETHERINGTON, and LOUIS MANTELL MCILDOWIE, subjects of the King of England, all residing in London, England, have invented certain new and useful Improvements in Apparatus for Cleaning Windows and Similar Purposes, of which the following is a specification.

- 10 This invention consists in a power-driven device primarily intended for cleaning windows but useful also for other purposes particularly where a surface to be cleaned is difficult of access by hand.
- 15 The device according to this invention essentially comprises in combination a portable motor (for example an electric motor) provided with handles or the like for holding it conveniently, and provided with a shaft which is extended outwards from it, and means for securing interchangeably to the free end of said extended shaft any one of a series of brushes, mops or other cleaning appliances.
- 20 Preferably, the device is provided with a change-speed gearing through which the extended shaft is driven by the motor; for example a gearing which provides a low speed and a high speed, the former for use in cleaning with wet brushes or mops, and the latter when polishing with dry mops.

The extended shaft may be made in sections each of which is provided with means at one end for readily connecting it to a driving shaft mounted permanently in the motor-casing, and connecting means at the other end to enable a cleaning appliance or another shaft-section to be readily secured thereto. By this means the length of the extended shaft may be varied to suit different requirements, and also the device may be packed into a small space by disconnecting all the shaft-sections.

Each shaft-section is preferably mounted in bearings in a casing which is provided with connecting means, such as bayonet-joints, at each end to enable them to be readily connected together end to end and to the end of a casing surrounding the driving shaft, and the ends of each shaft-section, as well as the end of the driving shaft, are provided with clutch members so situated as to be in engagement with each other when the casings are connected.

In order to secure ready interchangeability of the cleaning appliances the end shaft-section is provided with a bayonet socket or the like to engage and hold the suitably formed stubs of the cleaning appliances.

A device according to this invention is illustrated in the accompanying drawings, in which—

Figure 1 is an elevation of the device with parts of the extended shaft broken away; 65

Figure 2 is an elevation partly in section, and on a larger scale, of one of the shaft-sections;

Figures 3, 4, 5, 6 and 7 are elevations to the same scale as Figure 1 of various forms 70 of cleaning appliances; and

Figure 8 is a sectional elevation, to the same scale as Figure 2, of the change-speed gearing and the driving shaft, and showing 75 the end of one shaft-section coupled to the driving shaft.

The form of the invention illustrated comprises a small electric motor 2, the casing of which is extended at each end to form handles 4, 6. Current is led to the motor 80 through a long flexible cable 8 which passes through the handle 4 and is provided at its end with a plug which can be fitted into any ordinary lamp-socket. A switch for starting and stopping is provided, which is operated by a ring 10 rotating between stops at the end of the casing next to the handle 4. 85

The part of the casing next to the handle 6 contains a change-speed gearing, illustrated in Figure 8, which comprises a counter-shaft 12 driven from the motor-shaft 14 by gears 16, 18 and having fast to it two dissimilar pinions 20, 22 in mesh with two gears 24, 26 respectively, loose on a shaft 28 (hereinafter referred to as the driving shaft) either of which gears can be clutched to the driving-shaft by means of a sliding clutch member 30 splined to the shaft and capable of engagement with clutch-teeth 32 100 on either of the two gears. This clutch-member can be moved from outside the casing by means of a dog 34, engaging a groove 35 in the member 30, guided by means of a pin 36 sliding in guide-holes 38 in the casing, and provided with a knob 40 and a spring plate 42 which snaps into any one of three depressions 44 in the outer sur- 105

face of the casing, corresponding to the low speed, free and high speed positions of the gearing.

It is primarily intended that the low speed should be used with wet cleaning appliances, and the high speed with dry ones, and accordingly the two extreme positions of the knob 40 are marked "wet" and "dry" respectively on the casing, as shown in Figure 1. The motor and change-speed gearing are arranged, in the example shown, to give a low speed of 250 revolutions per minute, and a high speed of 1250 revolutions per minute.

15 The outer end of the driving shaft 28 is supported in ball-bearings in a hollow plug 46 screwed into the end of the handle 6 (Figure 8) and carries a dog-clutch member 48 which lies within the plug. The latter is provided with laterally projecting pins 50.

20 The hereinbefore-mentioned extended shaft is made in sections, one of which is shown in Figure 2. This shaft-section 52 is mounted in ball-bearings in a tubular casing 54, the right-hand or outer end 56 of which is of the same external diameter as the outer part of the plug 46 and has pins 58 similar to the pins 50.

25 The right-hand end of the shaft-section 52, not shown in the drawings, has a clutch member exactly similar to the clutch-member 48, the plug 46 with the clutch-member 48 being, in fact, identical in all respects with the end 56 of the casing 54 and the clutch member at the end of the shaft-section 52.

30 The left-hand or inner end of the casing 54 shown in Figure 8, is provided with a socket 60 capable of fitting over the plug 46 (or over the outer end of another similar casing 54) and provided with bayonet-joint slots 62 to engage the pins 50. The left-hand end of the shaft-section 52 is provided with a clutch-member 64 so situated as to engage the clutch-member 48 when the socket 60 and plug 46 are in engagement, as shown clearly in Figure 8.

35 It will be readily understood that a number of such shaft-sections and casings may be assembled end-to-end with the casings held rigidly in alignment and the shaft-sections coupled together. Two such sections are shown assembled in Figure 1.

40 In order to secure a brush or mop to the extended shaft, an end section, shown in Figure 2, is employed which consists of a short shaft 66 carrying a clutch-member 67 and mounted in ball-bearings in a socket 68 similar to the socket 60, so that it can be assembled with the outer end of any one of the shaft-sections, or with the plug 46 and the shaft 28. The outer end of the shaft 66 is provided with a socket 70 having bayonet-joint slots 72, and the studs 74 of the brushes 45 and mops shown in Figures 3 to 7 are made

to fit this socket 70 and are provided with pins 76 engaging the slots 72, so that any one of the brushes or mops may be readily secured to the outer end of the sectional extended shaft.

70 The appliance shown in Figure 3 is a conical brush 78, that shown in Figure 4 is a small mop 80 with a flexible neck 82 in the form of a helical spring. Figure 5 shows a cylindrical brush 84, and Figures 6 and 7 75 illustrate mops consisting of strips 86 of chamois leather or fabric secured to the stubs 74.

These appliances are shown only as examples, as it is obvious that any form of 80 cleaning appliance can be used.

85 The manner of using the device will be evident from the foregoing description, and it will be appreciated that windows, ceilings, shelves and other parts of a building 90 can be very thoroughly and expeditiously cleaned by means of the device with a minimum of exertion and in most cases without the use of ladders. Wet brushes or mops may be dried centrifugally by rotating them 95 for a few seconds at the high speed.

100 The position of the handles 4 and 6 is found to be particularly advantageous, as the centre of gravity of the device lies between them and their relatively wide separation allows the user to control and guide the device accurately with very little effort.

105 It is to be understood that the invention is not limited to the particular details described for the purpose of illustration but includes modifications which come within the scope of the appended claims.

110 What we claim as our invention and desire to secure by Letters Patent is:—

1. A cleaning device comprising in combination a portable motor, a change speed gearing, a driving shaft driven by said motor through said gearing, a casing surrounding said shaft, a plurality of extension casings, a plurality of shaft sections each mounted in bearings within an extension casing, connecting means at the ends of said extension casings and at the end of the casing surrounding the driving shaft, whereby said extension casings may be readily connected end to end and to the casing surrounding the driving shaft, clutch members on the ends of the shaft sections and on the driving shaft adapted to be in operative engagement with each other when the casings are connected together, and a cleaning device adapted to be operatively connected to the outer end of any one of said shaft sections.

115 2. A cleaning device comprising in combination a portable motor, a change speed gearing, a driving shaft driven by said motor through said change speed gearing and provided with a clutch member, a casing surrounding said shaft and provided with

a bayonet joint, an extension casing having bayonet joints at its ends one of which is adapted to be engaged with the bayonet joint on the casing surrounding the driving shaft to connect said two casings rigidly together, a shaft section mounted in bearings in the extension casing and having clutch members at its ends one of which is adapted to engage the clutch member on the driving 5 shaft when the casings are connected together, a second extension casing having a bayonet joint adapted to be engaged with the other bayonet joint of the extension casing first mentioned to connect the two 10 extension casings rigidly together, a second shaft section mounted in bearings in said 15

second casing and having at one end a clutch member adapted to engage the other clutch member of the first mentioned shaft section and having at its other end means for interchangeably securing thereto a cleaning appliance. 20

In testimony whereof we have signed our names to this specification in the presence of two subscribing witnesses.
